UNITED STATES PATENT OFFICE.

JAMES I. REYNOLDS, OF KANSAS CITY, MISSOURI.

LOOSE PULLEY FOR SEWING-MACHINES.

SPECIFICATION forming part of Letters Patent No. 244,671, dated July 19, 1881.

Application filed April 11, 1881. (Model.)

To all whom it may concern:

Be it known that I, JAMES I. REYNOLDS, of Kansas City, county of Jackson, State of Missouri, have invented certain new and useful Improvements in Loose Pulleys for Sewing-Machines; and I do hereby declare that the following is a full, clear, and exact description thereof, reference being had to the accompanying drawings, making a part of this specification, in which—

Figure 1 is a perspective view of the parts of my device separated from each other. Fig. 2 is a like view of said parts combined, and Fig. 3 is a side elevation of the same, a portion of the wheel being broken away to show the arrangement of the spring-pawl.

Letters of like name and kind refer to like parts in each of the figures.

The design of my invention is to enable the driving-wheel of a sewing-machine to be easily and cheaply arranged to revolve loosely upon its shaft when turned in a backward direction; and to this end it consists in the construction and combination of the parts of the device, substantially as and for the purpose hereinafter specified.

In the annexed drawings, A represents the driving-shaft, and B the driving-pulley, of a sewing-machine, which pulley is loosely journaled upon a reduced portion at one end of said shaft. The end of the shaft A is flush with or extends but slightly beyond the outer face of the hub b of the wheel B, and upon said end is placed a metal disk or washer, C, which is secured thereon by means of a screw, D, that passes axially into said shaft through an opening at the center of said disk. A pin, a, extends outward from the end of the shaft A into an opening, c, that is provided in the disk C, locks the latter to said shaft, and causes said parts to rotate together independent of the wheel B. Upon its inner face the disk C is provided with a circumferential incline, that terminates in a shoulder, c', similar to the tooth of a ratchet-wheel, and is engaged by a pawl, E, which is contained within a recess, b', that is formed in the hub b of the wheel B, said pawl being arranged to move longitudinally in a line with the shaft A, and being held with a yielding pressure outward against said disk by means of a spiral spring, F, which is placed within said recess, and at its outer end engages with a head

or enlargement, e, that is formed upon said pawl near its outer end. If, now, the wheel 55 B is rotated in one direction, the pawl E will engage with the shoulder or tooth c' of the disk C and cause the latter and the shaft A to revolve in the same direction; but if said wheel is rotated in the opposite direction said 60 pawl will be pushed rearward by the incline and pass over said shoulder without engagement, such arrangement causing said wheel and shaft to move together in one direction, while when rotated in an opposite direction 65 said wheel moves independent of and without disturbing said shaft.

In order that the mechanism may be applied to machines of different construction in which the driving-shafts move in opposite directions, 70 a shoulder or tooth, c', is provided upon each face of the disk C, and said teeth arranged in opposite directions, while the opening c is lengthened radially, so that to place the mechanism in position it is only necessary the wheel 75 B be loosened upon its shaft A, a round opening, b', drilled for the reception of the pawl E and spring F, and another opening provided in the end of said shaft for the reception of the dowel-pin, a, all of which can be done by 80 any ordinary mechanic in a few minutes of time.

I am aware that driving-wheels or loose pulleys have before been connected with shafts by means of spring-pawls, and therefore do 85 not claim the same, broadly.

Having thus fully set forth the nature and merits of my invention, what I claim as new is—

As a means for connecting together the 90 shaft A and wheel B, so as to cause the latter to move the former when rotated in one direction, the disk C, provided with the opening c and shoulder or tooth c', the pin a, projecting from said shaft into said opening c, the screw 95 D, passing through said disk into said shaft, and the spring-pawl E, contained within a recess in the hub of said wheel and adapted to engage with said shoulder c', said parts being combined to operate in the manner and for the 100 purpose substantially as specified.

Witness my hand this January 24th, 1881.

JAMES IRWIN REYNOLDS.

Attest:

JOHN S. HARBISON,
F. TITUS.
